[57] CLAIM

The ornamental design for a child-safe actuator for a
pressurized container, as shown.

DESCRIPTION

FIG. 1 is a perspective view of a child-safe actuator for
a pressurized container showing my new design;
FIG. 2 is a side elevational view;
FIG. 3 is a top plan view;
FIG. 4 is a rear elevational view; and
FIG. 5 is a front elevational view thereof.

FIG. 1

FIG. 2

FIG. 3

FIG. 4

FIG. 5
